UNITED STATES PATENT OFFICE

GERALD DEAKIN, OF ANTWERP, BELGIUM, ASSIGNOR TO WESTERN ELECTRIC COMPANY, INCORPORATED, OF NEW YORK, N. Y., A CORPORATION OF NEW YORK

TELEPHONE SYSTEM

Application filed April 30, 1927, Serial No. 187,968, and in Italy November 30, 1926.

This invention relates to telephone systems and has for its object the provision of improved means for extending telephonic connections between manual and machine switching offices.

One arrangement for the establishment of such connections, which has heretofore been proposed, used a three-way link circuit at the manual office, that is, a link circuit which was provided with three switches one of which associated the link with equipment located at the operator's position, a second which associated the link with an idle sender and a third which associated the link with an idle trunk to the machine switching office. In this arrangement, the link became a part of the connection when completed. A modification of this arrangement employed a link which was provided with switches performing the above mentioned functions but which, in addition, gave an indication to the operator of the selected trunk whereupon the connection was established independent of the link, which reverted to common use.

In accordance with the present invention, link circuits for associating an idle sender with an idle trunk and the equipment at the operator's position are eliminated, thereby reducing the amount of apparatus required. The extension of a calling line to a set of terminals individual to the wanted office causes the association of a sender with an idle trunk outgoing to that office, after which the trunk is associated with the terminals. When the connection has been established the sender is released. In addition, the sender is provided with means to test both the incoming and outgoing ends of the office trunk before appropriating it for use.

The preferred embodiment of the present invention, specifically stated, comprises jacks at the manual office allotted to the automatic offices to which the manual office has access, these jacks being connected to the banks of selector switches in which the interoffice trunks terminate. The operators at the manual office have access to these jacks by means of cord circuits of the usual character. There are a number of senders common to all of the jacks, each of which is provided with a selec-

tor switch which has access to the interoffice trunks. The insertion of a plug in a jack completes a start circuit for the trunk selectors of all idle senders. When a sender has found a trunk which is idle at its incoming end, it comes to rest and stops the trunk hunting operation of the remaining senders. It then tests the outgoing end of the trunk and, if that is also idle, establishes the necessary control circuits. As soon as a trunk has been selected, the jack selector of the trunk is operated to find the jack into which the operator has inserted her plug. As soon as the jack has been found, a key set at the operator's position is connected to the registers of the sender and the wanted number recorded. The sender then functions to control the extension of the connection over the switches of the automatic office, after which the talking conductors are connected through to the jack, the operator's key set is disconnected, and the sender is released to revert to common use.

The scope and purpose of the invention will be more clearly understood from a consideration of the following detailed description taken in connection with the attached drawings, in which:

Fig. 1 is a detailed showing of a sufficient part of the trunk circuit, sender, etc., to clearly set forth the invention; and

Fig. 2 is a skeleton diagram of the connection established by the apparatus of Fig. 1. Assuming that the subscriber at substation 100, located in a manual office, wishes to converse with the subscriber at substation 150, located in a machine switching office, he will remove his receiver from the switchhook, signaling the operator in the central office in the usual manner. The operator will insert the answering plug of cord circuit 102 in the line jack and receive from the wanted subscriber the number of the wanted subscriber's line. She will then insert the calling plug of the cord 102 in a jack, such as jack 103. A circuit is thereupon closed from battery in the cord circuit over the sleeve of the plug and sleeve of jack 103, winding of relay 104, resistance 105, to ground. A branch of this circuit extends to terminal 107 in the bank of jack finder 110 marking the jack to which the call

55

60

100

has been extended in the finder bank. Relay 104 operates, connecting the operator's key set to terminals 108 and 109 in the finder bank. It also closes a circuit from battery over its lower contact through resistances 111 and 112, winding of relay 113, resistance 160, to ground. A branch of this circuit extends from a point between resistances 111 and 112 to terminal 106 in the jack finder bank. Relay 113 operates, closing an obvious circuit for starting relay 114. Relay 114 in operating closes start circuits to all senders. In the case of those senders which are not in use with some other call, the start circuit is completed. For the sender shown, this may be traced from battery over the uppermost contact of relay 114, lower contact of jack 115, back contact of relay 116, winding of power magnet 117 of trunk finder 120, back contact of relay 113, conductor 130, lower left contact of cam 119 of the sequence switch which controls the operation of the sender, to ground through other apparatus of the sender, not shown. Magnet 117 is energized in this circuit, causing the brushes of the trunk finder to move over the terminals of the trunks appearing before it. Relay 114 closes a circuit from battery through its inner lower contact to all idle trunk circuits of the group. In the case of the trunk shown, the circuit may be traced from contact of relay 114, resistance 161, lower back contact of relay 134, to terminal 122. Assuming that the trunk shown is the first idle trunk encountered by the trunk finder 120, this circuit will be extended over the brush of the trunk finder, upper contact of jack 115, left high resistance winding of relay 118, to ground. Relay 118 operates, closing a circuit from battery through the winding of relay 129, front contact of relay 118, conductor 130, to ground, over the lower left contact of cam 119. Relay 129 operates, connecting ground over its outer left front contact to the right low resistance winding of relay 118. This reduces the potential of terminal 122 to render the trunk circuit busy to other senders.

Should two trunk finders, such as 120, simultaneously test the same trunk, the relays corresponding to relay 118 of each finder circuit would operate, in turn causing the operation of relays such as 129. The adjustment of relays 118 is such however, that two of them will not remain energized with their low resistance windings in multiple. Therefore both will release and hunting will continue.

The operation of relay 118 opens the above traced circuit for power magnet 117 and brings the brushes of finder 120 to rest. A test is now made of the outgoing end of the trunk. If the machine switching apparatus in which the trunk terminates at the mechanical office is in condition to extend the connection, the sequence switch associated there-

with will be standing in position 1 and ground will be connected to cam 132 over its lower contact. A circuit will therefore be closed as soon as the brushes of switch 120 come to rest, from battery through the winding of relay 131, inner left front contact of relay 129, brush of trunk finder 120 resting on terminal 125, upper back contact of relay 133, upper back contact of relay 134, over the tip conductor of the interoffice trunk 162, lower contact of cam 132, to ground. Relay 131 in operating prevents the finder from advancing further by opening a second energizing circuit of magnet 117 which otherwise would extend from magnet 117, over the left back contact of relay 131, right front contact of relay 129, to grounded conductor 130.

If ground were not connected to the tip conductor, relay 131 would not operate and the switch would advance again. As the switch leaves the terminals of the trunk, relay 118 releases, in turn releasing relay 129 and restoring the first energizing circuit of magnet 117. It therefore tests the incoming and outgoing ends of the next trunk in succession, as described for the first trunk.

Assuming that the trunk first tested is also free at the distant end, the operation of relay 131 closes an energizing circuit for power magnet 135, which controls the jack finder 110. This circuit may be traced from battery through the winding of magnet 135, terminal 127 and brush of trunk finder 120, back contact of relay 136, left front contact of relay 131, right front contact of relay 129, to grounded conductor 130. Switch 110 is rotated until contact is made with terminal 106, to which battery was connected through resistance 111. At this time a circuit is closed from battery on terminal 106 over the brush of the jack finder 110, inner lower contact of jack 137, terminal 126, left high resistance winding of relay 136, to ground at the right front contact of relay 131. Relay 136 operates, opening the circuit of power magnet 135, bringing the jack finder to rest on the terminals individual to jack 103. It also closes a circuit from battery through the winding of relay 116, front contact of relay 136, left front contact of relay 131, right front contact of relay 129, to grounded conductor 130. Relay 116 operates, connecting ground over its inner right contact to the right low resistance winding of relay 136, shunting the high resistance winding and marking the terminal 106 non-selectable to other jack finders. Relay 116 also closes a locking circuit for itself, extending from battery through its winding, front contact of relay 136, to ground at the outer right contact of relay 116. At its middle right contact, relay 116 closes an obvious contact for relay 138. At its left contact relay 116 disconnects battery from the energizing circuit of magnet 117. The connection of ground through a low

resistance to terminal 106 shunts the winding of relay 113, and that relay releases, in turn releasing relay 114 and removing battery from the sender start circuits and from the trunk test circuits. The release of relay 114 also opens the circuit of relay 118 which releases in turn releasing relay 129. With relay 129 released, ground is connected over its outer left back contact and the inner right front contact of relay 138 to maintain the busy condition on terminal 122.

Relay 138, in operating, closes a circuit from battery through the winding of relay 133, terminal 123, and the corresponding brush, middle right contact of relay 138, to ground at the upper right contact of cam 119. Relay 133, in operating, connects the operator's key set through to the registers of the sender, the circuit being traceable from the key set over the outer upper front contact of relay 104, terminal 109, upper front contact of relay 133, terminal 125, inner back contact of relay 129, outer left contact of relay 138, upper contact of cam 139 to the registers, back over the left contact of cam 140, middle left contact of relay 138, terminal 124, inner lower front contact of relay 133, terminal 108, inner upper front contact of relay 104, to the key set. The registers will now be set from the key set in any suitable manner, for example, as shown in the patent to Gerald Deakin, 1,653,890, granted Dec. 27, 1927.

Relay 133 in operating also closes a circuit from ground over its outer lower front contact, windings of relay 141 in series, upper contact of jack 137, terminal 107 to battery over the sleeves of jack 103 and the cord plug. Relay 141 closes an obvious circuit for busy lamp 142. It also closes a circuit from ground at its outer right front contact, resistance 144, and thence in parallel through the winding of relay 134 to battery and over terminal 121, outer right contact of relay 138, and winding of relay 145 to battery. Relay 145 operates to hold certain sender circuits open, but relay 134 cannot operate in parallel with relay 145. At its left contact relay 141 closes a link in an "all trunks busy" chain circuit. At its inner right front contact it prepares a circuit through its low resistance winding alone.

When the registers have been completely positioned, the sender sequence switch is advanced to position 3. At this time, the circuit of relay 133 is opened, and that relay releases, permitting the closure of a circuit from battery in the cord circuit 102, sleeves of the cord plug and jack 103, brush 107, upper contact of jack 137, low resistance winding and inner right contact of relay 141, to ground at the back contact of relay 133.

The release of relay 133 extends the tip and ring conductors of the interoffice trunk through to the selection control apparatus.

These circuits may be traced in part from battery through the selector relay 146, lower contact of cam 147, ring conductor of trunk 162, lower back contacts of relays 134 and 133, terminal 124, middle left contact of relay 138, right contact of cam 140, to the selection control apparatus and from ground over the lower contact of cam 132, over the tip of the trunk 162, upper back contacts of relays 134 and 133, terminal 125, inner left back contact of relay 129, outer left contact of relay 138, lower contact of cam 139, winding of stepping relay 148, resistance 149, to the selection control apparatus. Relays 148 and 146 operate in this fundamental circuit, relay 146 initiating the operation of the selector 151. The commutator represented schematically at 153 is moved with the selector switch, holding relay 146 operated and shunting relay 148 to cause the operation of the counting relays in the well known manner. Switch 151 is operated to select an idle final selector switch 152 which is then operated to select the called subscriber's line 150.

When relay 133 closed ground to the low resistance winding of relay 141 in shunt of its high resistance winding, the current through relay 104 was so reduced that that relay released, removing battery from the winding of relay 136. Relay 136 releases, in turn releasing relay 116. The release of relay 116 opens the energizing circuit of relay 138 but relay 138 remains operated over its inner left contact, upper left contact of cam 119, to ground. When the sender completes the selection of the called line, the sender sequence switch advances out of position 16. As soon as the sequence switch leaves position 16½, the locking circuit of relay 138 is opened, and that relay releases, disconnecting the control apparatus from the interoffice trunk. It also opens the circuit of relay 145 so that relay 134 now operates from ground at the right front contact of relay 141. The operation of relay 134 extends the tip and ring conductors of the trunk 162 to terminals 109 and 108 and thence over the back contacts of relay 104 to the tip and ring of jack 103 and the calling subscriber's line. The called line is signalled in the usual manner and the response of the subscriber extinguishes the supervisory signal in the operator's cord circuit. With relay 145 released, the sender relays are all released and the sender sequence switch is advanced to position 1 where it is ready to serve another call.

Fig. 2 is a skeleton of the circuit arrangement of Fig. 1. Corresponding units bear numbers in the second hundred corresponding to the numbers in the first hundred used in Fig. 1.

What is claimed is:

1. In a telephone system, a manual office, a machine switching office, trunks connecting said offices, an operator's position at said

5 manual office equipped with cord circuits and with jacks individual to said machine switching office, selection control equipment, means responsive to the connection of a cord circuit to one of said jacks to associate said control equipment with an idle one of said trunks, and means for thereupon associating said trunk with said jack.

10 2. In a telephone system, a manual office, a machine switching office, trunks connecting said offices, an operator's position at said manual office equipped with cord circuits and with jacks individual to said machine switching office, selection control equipment, means responsive to the connection of a cord circuit to one of said jacks to associate said control equipment with an idle one of said trunks, and means responsive to the association of said control equipment with said idle trunk for associating said trunk with said jack.

15 3. In a telephone system, a first office, a second office, trunks extending between said offices, a set of terminals at said first office individual to said second office, selection control equipment, a calling line, means for extending said calling line to said terminals, means responsive to the extension of said calling line to said terminals to cause the association of said control equipment with an idle one of said trunks, means for thereupon associating said trunk with said terminals, and means responsive to said control equipment to complete the connection over said trunk.

20 4. In a telephone system, a first office, a second office, trunks extending between said offices, a set of terminals at said first office individual to said second office, selection control equipment, a calling line, means for extending said calling line to said terminals, means responsive to the extension of said calling line to said terminals to cause the association of said control equipment with an idle one of said trunks, means responsive to the association of said control equipment with said idle trunk for associating said trunk with said terminals, and means responsive to said control equipment to complete the connection over said trunk.

25 5. In a telephone system, a first office, a second office, a plurality of trunks extending between said offices, a plurality of sets of terminals at said first office individual to said second office, a plurality of selection control devices, a calling line, means for extending said calling line to one of said sets of terminals, means responsive to the extension of said calling line to said terminals to cause all idle ones of said control devices to hunt for an idle one of said trunks, means responsive to the association of one of said control devices with an idle trunk to arrest the hunting operation of the other control devices and to cause said trunk to associate itself with said terminals, and means under the control of

said device for completing a connection over said trunk.

30 6. In a telephone system, a first office, a second office, a plurality of trunks extending between said offices, a switch individual to each trunk, a plurality of sets of terminals at said first office individual to said second office, a plurality of selection control devices, a switch individual to each control device, a calling line, means for extending said calling line to one of said sets of terminals, means responsive to the extension of said calling line to said terminals to cause the switch individual to each idle control device to hunt for an idle trunk, means responsive to the association of one of said control devices with an idle trunk to stop all of said switches and to cause the switch individual to the associated trunk to hunt for said terminals, and means effective following the association of said trunk with said terminals to complete the extension of the connection from said calling line under the control of said device.

35 7. In a telephone system, a plurality of trunks, each terminating in a switch, a selection control device including registers, an operator's position equipped with a key set, a plurality of jacks each appearing in a set of terminals at said switches and a cord circuit, means responsive to the connection of said cord circuit with one of said jacks to cause said selection control device to associate itself with one of said trunks, means thereupon effective to cause said trunk to associate itself with said jack, means also responsive to the connection of said cord circuit with said jack to associate said key set with the terminals of said jack whereby the association of said trunk with said jack completes the connection of said key set with said registers, and means operative following the actuation of said registers to disconnect said key set from said terminals.

40 8. In a telephone system, a plurality of trunks each terminating in a switch, a selection control device including registers, an operator's position equipped with a key set, a plurality of jacks each appearing in a set of terminals at said switch and a cord circuit, a relay operative upon the connection of said cord circuit with one of said jacks to connect said key set with the terminals of said jack, means controlled by said relay to cause said selection control device to associate itself with one of said trunks, means thereupon effective to cause said trunk to associate itself with said jack, means responsive to the association of said trunk with said jack to complete the connection of said key set with said registers, and means operative following the actuation of said registers to release said relay to disconnect said key set from said terminals.

45 9. In a telephone system, a plurality of trunks each terminating in a switch, a selec-

- tion control device including registers, an operator's position equipped with a key set, a plurality of jacks each appearing in a set of terminals at said switch and a cord circuit, a relay operative upon the connection of said cord circuit with one of said jacks to connect said key set with the terminals of said jack, means controlled by said relay to cause said selection control device to associate itself with one of said trunks, means thereupon effective to cause said trunk to associate itself with said jack, means responsive to the association of said trunk with said jack to complete the connection of said key set with said registers, and means operative following the actuation of said registers to close a low resistance shunt around said relay to release said relay and to disconnect said key set from said terminals.
10. In a telephone system, a plurality of trunks each terminating in a switch, a calling line, a selection control device including registers, an operator's position equipped with a key set, a plurality of jacks each appearing in a set of terminals at said switches and a cord circuit for extending said calling line to one of said jacks, a relay operative upon the insertion of the plug of said cord circuit in said jack to cause the connection of said key set with the terminals of said jack and to cause the association of said selection control device with one of said trunk circuits, means thereupon effective to cause said trunk circuit to associate itself with the terminals of said jack, means responsive to the association of said trunk with said jack terminals to complete the connection of said key set with said registers, and means operative following the actuation of said registers under the control of said key set to release said relay to disconnect said key set from said terminals and to extend said calling line to said trunk circuit.
11. In a telephone system, a plurality of trunks each terminating in a switch, a calling line, a selection control device including registers, an operator's position equipped with a key set, a plurality of jacks each appearing in a set of terminals at said switches and a cord circuit for extending said calling line to one of said jacks, a relay operative upon the insertion of the plug of said cord circuit in said jack to cause the connection of said key set with the terminals of said jack and to cause the association of said selection control device with one of said trunk circuits, means thereupon effective to cause said trunk circuit to associate itself with the terminals of said jack, means responsive to the association of said trunk with said jack terminals to complete the connection of said key set with said registers, and means operative following the actuation of said registers under the control of said key set to close a low resistance shunt around said relay to release said relay,
- disconnect said key set from said terminals, and extend said calling line to said trunk circuit.
12. In a telephone system, a trunk circuit, means for marking each end of said trunk as busy or idle, an electro-responsive device, means in said device for testing each end of said trunk, and means for associating said device with said trunk if both ends of said trunk are idle.
13. In a telephone system, a trunk circuit, means for marking each end of said trunk as busy or idle, an electro-responsive device, means in said device for successively testing each end of said trunk, and means for associating said device with said trunk if both ends of said trunk are idle.
14. In a telephone system, a trunk circuit, means for marking each end of said trunk as busy or idle, an electro-responsive device, means in said device for testing the first end of said trunk, means effective if said first end is idle to test the second end of said trunk, and means effective if said second end is also idle to associate said device with said trunk.
15. In a telephone system, a plurality of trunk circuits, means for marking each end of said trunk as busy or idle, an electro-responsive device, a switch individual to said device for connecting said device with said trunks, means to operate said switch, means to bring said switch to rest when a trunk is encountered one end of which is idle, means for thereupon testing the condition of the other end of said trunk, and means effective if said other end is busy to cause said switch to advance to the next trunk the first end of which is idle.
16. In a telephone system, a plurality of trunk circuits, means for marking each end of said trunk as busy or idle, an electro-responsive device, a switch individual to said device for connecting said device with said trunks, an operating magnet for said switch, means for establishing an operating circuit for said magnet, means to open said circuit when a trunk is engaged one end of which is idle, means for thereupon testing the condition of the other end of said trunk, and means effective if said other end is busy to establish a second circuit for said magnet to advance said switch to the next trunk one end of which is idle.
17. In a telephone system, a first office, a second office, a trunk extending between said offices terminating at said first office in a switch, means at each end of said trunk for marking said trunk busy or idle, a plurality of sets of terminals for said switch, a calling line, means for extending said calling line to one of said sets of terminals, an electro-responsive device, means in said device for testing each end of said trunk, and means controlled by said device to actuate said switch if

- said trunk is idle at both ends to extend said calling line to said second office.
18. In a telephone system, a first office, a second office, trunks extending between said offices each terminating in a switch at said first office, means at each office for marking said trunks busy or idle, a plurality of sets of terminals for said trunk switches, an electro-responsive device, a switch individual to each device, a calling line, means for connecting said calling line to one of said sets of terminals, means to operate the switch individual to said device, means to bring said switch to rest on a trunk one end of which is idle, means to thereupon test the other end of said trunk, and means effective if the other end of said trunk is busy to advance said switch to the next trunk one end of which is idle.
19. In a telephone system, a first office, a second office, trunks extending between said offices, means at said second office for marking the distant end of said trunks as busy or idle, a plurality of jacks at said first office individual to said second office, a plurality of electro-responsive devices, a switch individual to each device, an operating magnet for each switch, a calling line, a cord circuit for extending said calling line to one of said jacks, means responsive to the insertion of a plug of said cord circuit in said jack to mark the inner end of all idle trunks and to establish start circuits for the operating magnets of all idle devices, means to open the start circuit of a magnet when the switch controlled thereby engages a trunk, the inner end of which has been marked idle, means to thereupon test the distant end of said trunk, means effective if the distant end of said trunk is busy to establish a second circuit for said magnet to advance said switch to the next trunk the inner end of which has been marked idle.
20. In a telephone system, a first office, a second office, trunks extending between said offices, means at said second office for marking the distant end of said trunks as busy or idle, a plurality of jacks at said first office individual to said second office, a plurality of electro-responsive devices, a switch individual to each device, an operating magnet for each switch, a calling line, a cord circuit for extending said calling line to one of said jacks, means responsive to the insertion of a plug of said cord circuit in said jack to mark the inner end of all idle trunks and to establish start circuits for the operating magnets of all idle devices, means to open the start circuit of a magnet when the switch controlled thereby engages a trunk, one end of which has been marked idle, means to thereupon test the distant end of said trunk, means effective if the distant end of said trunk is idle to open the start circuits of the other control devices and to complete the association of said device with said trunk.
